TREATMENT OF HYDROCARBON OILS

Gustav Egloff, Chicago, Ill., assignor to Universal Oil Products Company, Chicago, Ill., a corporation of Delaware

Application March 21, 1940, Serial No. 325,108

8 Claims. (Cl. 196—10)

This invention relates to the catalytic treatment of intermediate boiling range fractions produced in the primary non-cracking distillation of petroleum although similar or analogous material from other sources may also be treated.

More specifically the invention has reference to a method whereby gas oils are treated in a series of cooperating steps with the object of ultimately producing relatively high yields of iso-paraffins which are utilizable directly as aviation fuel or in blend with gasolines inferior in anti-knock value to improve their quality.

It has come to be recognized that there are limitations to both yield and quality of motor fuels producible by the thermal treatment of petroleum fractions and also that there are some limitations to the yields and types of motor fuels obtainable when catalysts are employed. The present process involves primarily the catalytic cracking of gas oil fractions with primary fractionation of the products and the selective thermal cracking of certain gaseous fractions to produce olefins for alkylating other original gaseous fractions, this combination of steps leading ultimately to the production of higher antiknock saturated gasoline fractions of an iso-paraffinic character than are producible by processes involving merely thermal or catalytic cracking in a single stage type of operation.

In one specific embodiment the present invention comprises subjecting intermediate boiling range hydrocarbon fractions to thermal treatment in the presence of catalysts comprising ferric chloride and aluminum chloride to produce relatively high yields of butanes, fractionating the products to produce a normal butane fraction and an iso-butane fraction, thermally cracking said normal butane fraction to produce high yields of olefins of 2, 3, and 4 carbon atoms to the molecule, and alkylating iso-butane with the olefins thus produced in the presence of selected catalysts.

The process of the invention may conveniently be described in connection with the attached drawing which shows diagrammatically in general side elevation a combination of interconnected apparatus in which the process may be carried out.

Referring to the drawing, gas oils may be admitted to a charging pump 3 by way of a line 1 containing valve 2, pump 3 discharging through line 4 containing valve 5 into and through a heating element 11 disposed to receive heat from a furnace 12.

Ferric chloride and/or aluminum chloride cata-

lysts in substantially anhydrous condition may be admitted to a pump 8 from a line 6 containing a valve 7 in suspension in an oil which may be a portion of the charging oil admitted to pump 3 or may be an oil of a different character, pump 8 discharging through a line 9 containing valve 10 into the line 4 so that the catalyst is slurried in charging stock passing through the heating element. Insufficiently converted materials are returned to line 4 by way of line 19 as will be presently described.

The object of the first catalytic cracking step is to produce as high yields of butanes as possible and a unit is therefore preferably operated at a relatively high recycle ratio, the temperature employed at the exit of heater coil 11 being of the order of 500-700° F., depending upon the character of the stock being processed while any desired pressure may be maintained with the object of controlling the time factor and the rate and character of the reaction. I have found that at a high recycle ratio and moderate temperatures of operation high yields of butanes are produced which constitute stocks for further treatment to produce the iso-paraffins which are the ultimate object of the process.

It is characteristic of the present process operating with the catalysts and in the manner described that there is a very low production of unsaturated hydrocarbons and a relatively high production of iso-paraffinic hydrocarbons. The olefins are produced only in inconsiderable quantities, and as a rule the production of normal butane is considerably less than the production of iso-butane so that there is need for introducing olefinic materials from outside sources if the iso-butane production is to be completely alkylated.

The heated materials from heater coil 11 pass through line 13 containing valve 14 and into a fractionator 15 of suitable design and construction to permit the efficient separation of fixed gases having a lower molecular weight than butanes which are released through line 21 containing valve 22 and disposed of in any desired manner and to permit the separate production of iso-butane and of normal butane which are indicated as being removed from the fractionator as individual side-cuts. In actual practice, however, a considerably more complicated fractionating system will be necessary to insure the separation of iso-butane and normal butanes which may involve use of several fractionating columns with one particularly designed to handle and fractionate hydrocarbons having five carbon atoms

and less to the molecule. As shown in the drawing an iso-butane fraction boiling at approximately 10° F. is shown diagrammatically as being removed from an accumulator plate 23 by way of line 25 containing valve 26 and passed to an alkylation unit which will be presently described. From the same fractionator a lower accumulator plate 24 is indicated as furnishing normal butane which is withdrawn through line 38 containing valve 31 and thermally cracked to produce olefins for the alkylation of the i-butane. If desired a high antiknock aviation gasoline fraction may be removed as a side-cut from the fractionating column. Insufficiently converted refluxes are withdrawn from the bottom of fractionator 15 through line 16 containing valve 17 to a recirculating pump 18 which discharges through line 19 containing valves 20 and 20' and back to line 4 as previously described. The reflux removed at this point will contain partly spent metal halide catalysts which may be continuously withdrawn in part through valve 20' while fresh catalyst is introduced through line 6 as makeup. By proper manipulation and withdrawal of a certain proportion of the spent material formation of catalyst sludges and coky residues can be substantially prevented. The use of proportioned mixtures of ferric chloride and aluminum chloride is preferred since the ferric chloride moderates the activity of the aluminum chloride and permits the production of relatively higher yields of the desired butanes.

It is preferable to have present relatively small amounts of hydrogen chloride which may be added along with the original slurry of catalysts or which may be separately injected into the line conveying the catalyst and oil to be treated to the heating and fractionating zones although means for this purpose are not indicated in the drawing. Similarly, recirculation apparatus used conventionally to return a portion of overhead condensate to the top of fractionator 15 to control and regulate the fractionation therein have not been shown.

A normal butane fraction from line 38 is taken by pump 32 and discharged through line 33 containing valve 34 into and through the heating element 35 arranged to receive heat from a furnace 36. If necessary the normal butane fraction may be cooled and liquefied in order to prevent difficulties in the operation of pump 32. The conditions which have been found to be optimum for cracking normal butane to produce particularly high yields of butenes have been found to temperatures of the order of 900-1200° F. and times at reaction temperature of the order of 5-75''. Under these conditions as will be shown in later examples, yields of butenes as high as 20% per pass (based on n-butane decomposed) are obtainable along with production of ethylene and propylene and other gases.

The heated and converted materials from heating element 35 pass through line 37 containing valve 38 (preferably with quenching to stop undesirable reactions) to fractionator 39 which represents fractionating equipment of a suitable design and construction to permit the production of relatively short individual gaseous fractions. For example, the fractionating system is preferably operated to produce an incondensable gas containing all those lighter than ethylene which are released through line 42 containing valve 43. An accumulator plate 44 may then accumulate an ethane-ethylene fraction which is withdrawn through line 45 containing valve 46 while accu-

mulator plates 47, 50 and 53 accumulate propene, iso-butene, and normal butene fractions respectively which are withdrawn through line 48 containing valve 49, line 51 containing valve 52 and line 54 containing valve 55. Fractionator 39 is provided with a bottom draw line 46 containing a valve 41 for the removal of heavy material. In the drawing, fractionator 39 has been very simply indicated whereas in actual practice in the operation of the process, considerably more extensive equipment will be required. However, equipment is readily available which is competent to effect the desired separations.

As already indicated in a normal operation of the present process the normal butane produced and separated will be considerably less than the iso-butane so that the most general practice is to add some olefin-containing gases from an outside source such as those produced in an ordinary thermal cracking process. For this purpose line 37 containing valve 38' is indicated as a point of entrance for such gases prior to the fractionator 39 and line 28' containing valve 29' is indicated as an alternate point of introduction directly prior to the alkylation step.

It is comprised within the scope of the present invention to alkylate the separated iso-butane with any or all of the olefinic hydrocarbons produced in the cracking of a normal butane. However, in the interest of simplicity the description of the process given in connection with the drawing will be limited to the alkylation of the iso-butane with the combined olefin production which is passed through line 46 to line 28 leading to line 58 which admits alkylating catalysts which may be sulfuric acid, either cold or hot, hydrogen fluoride, boron fluoride, aluminum chloride alone or on supports or other efficient catalysts, these being introduced through line 56 containing valve 57 to catalyst pump 58 which discharges through line 59 containing valve 60 into the stream of mixed olefin-iso-butane hydrocarbons. Since alkylation reactions are generally of an exothermic character the reactants and catalyst are preferably cooled during passage through a cooling coil 61 disposed in a cooler 62 and then passed through line 63 containing valve 64 through an alkylator 65 wherein time is given for the effecting of the desired alkylation reaction. It will be appreciated that the alkylation unit comprising broadly cooler 62 and alkylator 65 is only diagrammatic and that different modes of operation may be employed. For example, in addition to the flows shown in the drawing a granular alkylation catalyst such as, for example, aluminum chloride supported on a porous granular material such as activated carbon may constitute filling material for the alkylator and the necessity for separation of this catalyst from the reaction products is therefore obviated. Furthermore, in any type of alkylation the apparatus may be employed in multiple connection where catalyst recovery is necessary in order to insure the continuity of the operation. The reactants passing through line 66 containing valve 67 pass to a receiver and separator 68 wherefrom separated gases may be withdrawn through line 69 containing valve 70 and separated and partly spent catalyst may be returned by way of line 71 containing valve 72 to pump 73 and discharge line 74 containing valve 75 back to line 59 for further use. A portion of spent catalyst may be discharged continuously or intermittently through line 74' and

valve 78' while makeup is supplied through line 56.

It is to be emphasized that the description of the alkylation step is principally illustrative and it is to be understood that it is within the scope of the invention to separately alkylate individual fractions of iso-butane with ethylene, propylene, iso and normal butylene. When alkylating with ethylene thermal reaction may be brought about at temperatures of the order of 950° F. and pressures of the order of 1000-5000 lbs./sq.in. to produce neo-hexane, and similar results may be obtained using milder conditions of operation and hydrogen fluoride and/or boron fluoride catalysts. When alkylating with propene, it is preferred to use hydrogen fluoride catalysts; when alkylating with iso-butene or normal butene, it is preferred to employ sulfuric acid of approximately 90-100% concentration and normal atmospheric temperatures, say from 10-30° C. When using phosphoric acid and particularly the so-called solid phosphoric acid catalysts, the best alkylation results are obtained when using temperatures of the order of approximately 200-400° C. and pressures of the order of 2000-5000 lbs./sq.in. not claimed individually in the present process but only in combination with the other features which constitute the patentable process.

By the use of the separate alkylation steps described, it is possible to produce a series of iso-paraffins having extremely high anti-knock value in combination with fuels at present marketed, these iso-paraffins including neo-hexane, iso-heptanes, and iso-octanes. To separate these compounds, the products of the alkylation are withdrawn from accumulator 68 through line 76 containing valve 77 to a pump 78 which discharges through a line 79 containing a valve 80 into and through a heating element 81 disposed to receive heat from a furnace 82 in which sufficient heat is imparted to the alkylate so that it can be fractionated. The heated materials passing through a line 83 containing valve 84 to a fractionator 85 having a bottom draw line 86 containing a valve 87 for the removal of heavier alkylated material than is desired in the final product or products. As shown in the drawing, vapors from fractionator 85 pass through vapor line 88 containing valve 89 through a condenser 90, the cooled material passing through run-down line 91 containing valve 92 to a final receiver 93 for finished product. This receiver has a conventional gas release line 94 containing a valve 95 and a line for the desired liquid product 96 containing valve 97. It is obviously within the scope of the invention to operate fractionator 85 to produce a series of side cuts consisting of fractions predominating in some of the individual hydrocarbons produced as the result of the separate or combined alkylation reactions.

The following illustrative example is introduced at this point to show the type of results and yields of products to be normally expected in the practical operation of the process although the data are not introduced with the intention of limiting the proper scope of the invention.

A Mid-Continent gas oil is cracked in the presence of approximately 10% by weight of an equimolar mixture of a substantially anhydrous ferric chloride and aluminum chloride, adding a small amount of hydrogen chloride. There is produced approximately 35% by weight of iso-butane and 10% by weight of normal butane while utilizing a temperature of approximately 75

650° F. at an exit of the heating element of the catalytic cracking unit.

The normal butane product is subjected to pyrolysis to produce therefrom about 50% of a mixture of olefins comprising ethylene, propene, iso-butene, and normal butene and to supplement the olefin production the mixture of gases obtained in the stabilization of a cracked naphtha and comprising 40% by volume of mixed normally gaseous olefins is introduced in sufficient quantity to provide an amount of olefins approximately equivalent to those produced in the thermal treatment of a normal butane. The iso-butane is thereupon alkylated in the presence of sulfuric acid at a temperature of 70° F. so that there is ultimately produced from the gas oil charge, a mixture consisting essentially of iso-paraffinic hydrocarbons boiling within the approximate range of 100-400° F. and showing an octane number of 85 by the motor method. In the alkylation step an excess of iso-butane is maintained at all times to limit the tendency toward polymerization and ester formation among the olefins.

I claim as my invention:

1. A process for treating petroleum fractions to produce therefrom substantial yields of essentially paraffinic motor fuel having relatively high antiknock value which comprises subjecting an intermediate boiling range petroleum fraction to treatment at an elevated temperature and pressure in the presence of a catalyst consisting essentially of a mixture of ferric chloride and aluminum chloride with a minor amount of hydrogen chloride to produce a substantial yield of iso-butane and normal butane, separating said iso-butane and said normal butane, thermally cracking said normal butane at an elevated temperature and pressure and for a time of reaction adequate to produce a substantial yield of olefinic hydrocarbons, alkylating said iso-butane with said olefinic hydrocarbons and fractionating the products of the alkylation step to recover high anti-knock value gasoline.

2. A process for treating petroleum fractions to produce therefrom substantial yields of essentially paraffinic motor fuel having relatively high antiknock value which comprises subjecting an intermediate boiling range petroleum fraction to treatment at an elevated temperature of the order of 500-700° F. and a superatmospheric pressure in the presence of a catalyst comprising essentially a mixture of ferric chloride and aluminum chloride with a minor amount of hydrogen chloride to produce a substantial yield of iso-butane and normal butane, separating said iso-butane and said normal butane, thermally cracking said normal butane at an elevated temperature under pressure and for a time of reaction adequate to produce a substantial yield of olefinic hydrocarbons, alkylating said iso-butane with said olefinic hydrocarbons and fractionating the products of the alkylation step to produce high antiknock value gasoline.

3. A process for treating petroleum fractions to produce therefrom substantial yields of essentially paraffinic motor fuel having relatively high antiknock value which comprises subjecting an intermediate boiling range petroleum fraction to treatment at an elevated temperature of the order of 500-700° F. and a superatmospheric pressure in the presence of a catalyst comprising essentially a mixture of ferric chloride and aluminum chloride with a minor amount of hydrogen chloride to produce substantial yields of iso-

butane and normal butane, separating said iso-butane and said normal butane, thermally cracking said normal butane at an elevated temperature under pressure and for a time of reaction adequate to produce a substantial yield of olefinic hydrocarbons, alkylating said iso-butane with said olefinic hydrocarbons and similar hydrocarbons introduced from a source extraneous to the process, and fractionating the products of the alkylation step to recover the resultant high antiknock value gasoline.

4. A process for treating petroleum fractions to produce therefrom substantial yields of essentially paraffinic motor fuel having relatively high antiknock value which comprises subjecting an intermediate boiling range petroleum fraction to treatment at an elevated temperature of the order of 500-700° F. and a superatmospheric pressure in the presence of a catalyst consisting essentially of a mixture of ferric chloride and aluminum chloride with a minor amount of hydrogen chloride to produce substantial yields of iso-butane and normal butane, separating said iso-butane and said normal butane, thermally cracking said normal butane at an elevated temperature under pressure and for a time of reaction adequate to produce a substantial yield of olefinic hydrocarbons, alkylating said iso-butane with said olefinic hydrocarbons and similar hydrocarbons introduced from a source extraneous to the process, in the presence of sulfuric acid of approximately 90-100% concentration, and fractionating the products of the alkylation step to recover the resultant high antiknock value gasoline.

5. A process for treating petroleum fractions to produce therefrom substantial yields of essentially paraffinic motor fuel having a relatively high antiknock value which comprises subjecting an intermediate boiling range petroleum fraction to treatment at an elevated temperature of the order of 500-700° F. and a superatmospheric pressure in the presence of a catalyst comprising essentially a mixture of ferric chloride and aluminum chloride with a minor amount of hydrogen chloride to produce substantial yields of iso-butane and normal butane, separating said iso-butane and said normal butane, thermally cracking said normal butane at an elevated temperature under pressure and for a time of reaction adequate to produce a substantial yield of olefinic hydrocarbons, alkylating said iso-butane with said olefinic hydrocarbons and similar hydrocarbons introduced from a source extraneous to the process in the presence of a granular phosphoric acid-containing catalyst and fractionating the products of the alkylation step to produce the desired high anti-knock value gasoline.

6. A process for treating petroleum fractions to produce therefrom substantial yields of essentially paraffinic motor fuel having relatively high antiknock value which comprises subjecting an intermediate boiling range petroleum fraction to treatment at an elevated temperature of the order of 500-700° F. and a superatmospheric pressure in the presence of a catalyst consisting es-

sentially of a mixture of ferric chloride and aluminum chloride with a minor amount of hydrogen chloride to produce substantial yields of iso-butane and normal butane, separating said iso-butane and said normal butane, thermally cracking said normal butane at an elevated temperature under pressure and for a time of reaction adequate to produce a substantial yield of olefinic hydrocarbons, alkylating said iso-butane with said olefinic hydrocarbons and similar hydrocarbons introduced from a source extraneous to the process in the presence of sulfuric acid of approximately 90-100% concentration at a temperature of the order of 10-30° C. and fractionating the products of the alkylation step to recover the resultant high antiknock value gasoline.

7. A process for treating petroleum fractions to produce therefrom substantial yields of essentially paraffinic motor fuel having a relatively high antiknock value which comprises subjecting an intermediate boiling range petroleum fraction to treatment at an elevated temperature of the order of 500-700° F. and a superatmospheric pressure in the presence of a catalyst comprising essentially a mixture of ferric chloride and aluminum chloride with a minor amount of hydrogen chloride to produce substantial yields of iso-butane and normal butane, separating said iso-butane and said normal butane, thermally cracking said normal butane at an elevated temperature under pressure and for a time of reaction adequate to produce a substantial yield of olefinic hydrocarbon, alkylating said iso-butane with said olefinic hydrocarbon and similar hydrocarbon introduced from a source extraneous to the process in the presence of a granular phosphoric acid-containing catalyst at a temperature of the order of 200-400° C. and a pressure of the order of 2000-5000 pounds per square inch and fractionating the products of the alkylation step to recover therefrom high antiknock value gasoline.

8. A process for treating petroleum fractions to produce therefrom substantial yields of neo-hexane which comprises subjecting an intermediate boiling range petroleum fraction to treatment at a temperature of the order of 500-700° F. and a superatmospheric pressure in the presence of a catalyst comprising essentially a mixture of ferric chloride and aluminum chloride with a minor amount of hydrogen chloride to produce substantial yields of iso-butane and normal butane, separating said iso-butane and said normal butane, thermally cracking said normal butane at an elevated temperature under pressure and for a reaction period adequate to produce a substantial yield of ethylene, alkylating said iso-butane with said ethylene and a further amount of ethylene introduced from a source extraneous to the process, at a temperature of the order of 900-1000° F. and a pressure of the order of 1000-5000 pounds per square inch to produce substantial yields of neo-hexane, and fractionating the products of the alkylation step to substantially separate the desired neo-hexane.

GUSTAV EGLOFF.
